BARBER'S CHAIR WITH ACCESSORIES
COMPARTMENTS

Frank J. Strok, Phillips, Wis.

Application February 2, 1951, Serial No. 209,060

2 Claims. (Cl. 155—188)

1

The present invention relates to accessories for barbers' chairs and it consists in the combinations, constructions and arrangements of parts herein described and claimed.

Generally there is provided a barber's chair in which the back thereof is formed in a novel manner to provide a plurality of racks and containers wherein may be stored for ready access such devices as, for example, a hair brush, a whisk broom, a powder can, bottles containing toilet water, witch hazel and the like, shears, razors, combs, etc. The device is so formed that all of the articles mentioned may be readily moved from and returned to their positions in the rear of a conventional barber's chair.

It is accordingly an object of the invention to provide a device of the character set forth which is simple in construction, inexpensive to manufacture and yet effective and efficient in use.

Another object of the invention is the provision of a device of the character set forth which will render it unnecessary for a barber to store his tools and accessories at a point remote from his working position, namely the immediate vicinity of the barber's chair.

Another object of the invention is the provision, in a device of the character set forth, of novel means for racking and storing the conventional tools and accessories utilized by a barber in the performance of his work.

Other and further objects of the invention will become apparent from a reading of the following specification taken in conjunction with the drawing, in which:

Figure 1 is a fragmentary rear elevational view of a barber's chair utilizing an embodiment of the invention.

Figure 2 is a fragmentary sectional view taken along line 2—2 of Figure 1.

Figure 3 is a fragmentary sectional view taken along line 3—3 of Figure 1.

Figure 4 is a sectional view taken substantially along line 4—4 of Figure 1, and

Figure 5 is an enlarged fragmentary rear elevational view similar to Figure 1 but showing a certain compartment door forming a part of the invention in opened condition.

Referring more particularly to the drawing, there is shown therein a conventional barber's chair having a base 10, upon which is mounted a seat 11 from each side of which extends an arm rest 12 and to the rear of which seat 11 there is hingedly connected, as indicated at 13, a conventional back rest 14.

The rear of the back rest 14 is formed with a

2

hollow box-like structure having a top 15, a bottom 16, an inner wall 17 and an outer wall 18.

The outer wall 18 may be removably affixed to the remaining structure by means of a screw 19 which connects the upper end of the same with a dependent tab 20 and may be provided with an indented flange 21 along its lower edge which flange is adapted to engage the rear of an up-standing marginal portion 22 extending upwardly from the bottom 16.

The outer wall 18 is provided with a pair of rounded indentations 23 for the reception therein of the rear halves of bottles 24 and 25 which are adapted to contain witch hazel, toilet water or the like. Adjacent the upper ends of each of the indentations 23 there is provided a pair of clamp members 26 which are adapted to releasably engage the necks of the bottles 24 and 25.

Disposed in the outer wall 18 is a vertically extending rectangular indentation 27 adjacent the upper end of which there is mounted a hook 28 upon which may be suspended a neck brush 29 and in the lower end of the indentation 27 there is provided a pair of clamp members 30 wherein may be removably mounted a bottle 31 adapted to contain powder or the like.

A compartment 32 is provided in the outer wall 18 preferably above the indentations 23 and this compartment 32 is provided with a hinged door 33 having a glass window 34 therein and provided with a conventional operating knob and latch 35. The compartment 32 extends downwardly below the lower end of the door 33, as indicated at 37 so that a can 38 of sterilizing liquid may be mounted in the lower end thereof. A hair brush 39 is adapted to be removably mounted in the compartment 32 by means of a pair of clamp members 40, as shown in Figure 5.

A compartment 41 of substantially rectangular shape is formed in the outer wall 18 preferably in the lower corner thereof remote from the indentations 23. This compartment 41 is provided with a door 42 having a handle 43 and a centrally disposed opening 44 and is hinged, as indicated at 45, along its lower horizontal edge. The compartment 41 is adapted to contain vertically therein a plurality of sanitary neck strips 46. Immediately above the compartment 41 there is provided a compartment 47 having a door 48 hinged at its lower horizontal edge, as indicated at 49, and which door 48 is provided with an operating handle 50 adjacent its upper end. The handle 50 is adapted to operate a latch 51.

The upper end of the compartment 41 forms a shelf 52 for the compartment 47 and a can 53 of

liquid disinfectant is adapted to rest upon the shelf 52. The inner side of the door 48 is centrally provided with an inwardly extending shelf 54 which is perforated, as indicated at 55, in its lower portion and the compartment 47 is adapted to contain therein tools such as scissors, razors, and the like, the same being mounted in the perforations 55 in the shelf 54.

In use, it will be apparent that all of the various tools and accessories needed by a barber may be mounted within the various compartments and depressions above described and that, further, the compartment 32 may be kept constantly in a sterilized condition by means of the can of disinfectant 38 mounted therein while the compartment 47 and the tools therein contained may be likewise kept in a sterilized condition by means of the can 53 of disinfectant contained in the lower end of such compartment. The sanitary paper neck pieces 46 may be easily removed, one at a time, through the opening 44 in the cover 42 and it will be further apparent that the barber utilizing a chair in accordance with this invention may remove and replace the various articles above described without the necessity of leaving his operating position adjacent the chair to secure and return such articles in the conventional manner thus saving a great deal of time and unnecessary work for the barber.

While but one form of the invention has been shown and described herein, it will be readily apparent to those skilled in the art that many modifications may be made without departing from the spirit of the invention or the scope of the appended claims.

What is claimed is:

1. A device of the character described comprising a barber chair having a back rest provided

5 with a hollow rear portion having an outer wall and an inner wall, said outer wall having a plurality of depressed portions each adapted to receive therein a barber's accessory, clamp members arranged adjacent each side of each of said depressed portions for releasably maintaining said accessories in position in its respective depressed portion, compartments formed in said outer wall, and doors for each of said compartments.

10 2. A device of the character described comprising a barber chair having a back rest provided with a hollow rear portion having an outer wall and an inner wall, said outer wall having a plurality of depressed portions each adapted to receive therein a barber's accessory, clamp members arranged adjacent each side of each of said depressed portions for releasably maintaining said accessories in position in its respective depressed portion, compartments formed in said outer wall, and doors for each of said compartments, said outer wall being removably mounted with respect to the rear portion of said back rest.
